UNITED STATES PATENT OFFICE.

EVARTS G. LOOMIS, OF NEWARK, NEW JERSEY, ASSIGNOR TO THE ARLINGTON COMPANY, OF ARLINGTON, NEW JERSEY, A CORPORATION OF NEW JERSEY.

APPARATUS FOR MIXING MATERIALS WITH FLUIDS.

1,324,774.

Specification of Letters Patent.

Patented Dec. 9, 1919.

Application filed December 12, 1916. Serial No. 136,412.

To all whom it may concern:

Be it known that I, EVARTS G. LOOMIS, of Newark, in the county of Essex, and in the State of New Jersey, have invented a certain new and useful Improvement in Apparatus for Mixing Materials with Fluids, and do hereby declare that the following is a full, clear, and exact description thereof.

My invention relates to an apparatus for 10 mixing materials with fluids and has for its object to provide an apparatus adapted to be utilized in the application of the invention to the mixing of nitrocellulose with water, for the purpose of suspending the 15 fibers of the nitrocellulose in the water, so that it can be transported through pipes. It has been difficult heretofore to convey certain kinds of nitrocellulose through pipes, even when mixed with water by the best-known means, as the mixture frequently 20 clogs in the pipes owing to imperfect mixing.

Referring to the illustrated application of my invention, it is well known that nitrocellulose is made by treating cellulose in an acids bath. When the chemical reaction is completed, it is necessary to remove the excess acids from the resulting nitrocellulose. The general practice is to remove as 25 much of the acids as possible by a fluid-extracting apparatus and then remove the remainder of the acids by washing. The common practice is to dump the nitrocellulose from the fluid-extracting apparatus 30 into a washing tank. As the addition of small quantities of water to the acid-wet nitrocellulose will cause the nitrocellulose to decompose, particularly in any lumps in the mass, it is necessary to break up the 35 lumps and mix all the fibers of the nitrocellulose with water as quickly as possible. This is done ordinarily by workmen, who break up the lumps and mix the nitrocellulose with the water by the use of ordinary 40 hand forks. This operation is called drowning. The fumes given off by this operation are so intense that it is difficult to perform the work properly or obtain workmen willing to perform this operation.

50 The features of invention, therefore, which enter into combination with the mixing apparatus, are adapted to prevent the escape of acid fumes, to feed the nitrocellulose in the required quantities and condi-

tion to the mixing device, to mix the nitrocellulose thoroughly with the water as quickly as possible (drowning) to prevent decomposition, and to convey the nitrocellulose to the washing device. The apparatus described herein and chosen to illustrate 60 the invention, therefore, may be described as a combined drowning, mixing, and conveying apparatus.

The object of my invention as applied to the present embodiment thereof is to 65 convey the nitrocellulose directly from the fluid-extracting apparatus to the washing apparatus without manual handling and in such a manner as to prevent the nitrocellulose from decomposing and from diffusing 70 the acid fumes.

Other objects of my invention will be apparent from the following description, in which—

Figure 1 is a side elevation of a combined 75 drowning, mixing, and conveying apparatus with a fluid-extracting apparatus and washing machine shown diagrammatically in connection therewith;

Fig. 2 a side elevation of the combined 80 drowning, mixing, and conveying apparatus with parts broken away;

Fig. 3 a section taken on the line 3—3 of Fig. 2 looking in the direction of the arrows;

Fig. 4 a vertical view of the mixing device;

Fig. 5 a plan of the bladed screw of the mixing device; and

Fig. 6 a perspective of a conveyer bar.

Similar reference characters refer to similar parts throughout the drawings.

In the embodiment chosen to illustrate the invention and referring to Fig. 1, reference characters E represent fluid-extracting apparatus of any desired type, such, for example, as centrifugal machines. If the fluid-extracting apparatus E are placed directly over the combined drowning, mixing, and conveying apparatus C, as shown in Fig. 1, the bottoms of the fluid-extracting apparatus may be removed in any desired manner as by raising, so that the nitrocellulose may be pushed from the sides of the centrifugals directly to the combined drowning and mixing apparatus. A washing apparatus, such, for example, as a washing machine of any desired type is illustrated diagrammatically at W, the scale being reduced owing to the

limits of the drawing. The centrifugal machines E and washing machine W may be located at any desired place with reference to the combined drowning and mixing apparatus, the present drawings showing a convenient arrangement for purposes of illustration.

In the combined drowning and mixing apparatus, the nitrocellulose first is received from the fluid-extracting apparatus in clam shells 1, of which two are illustrated in the present embodiment of the invention. These clam shells when closed form a chute closed at the top thereby preventing the escape of fumes. Each clam shell opens into a chute 2, which leads to a feeding device of any desired type. The sides of the clam shell when closed preferably form part of or a continuation of the walls of the chute, and the walls of the chute preferably increase in horizontal cross-section from top to bottom.

In the present embodiment, a feeding device of any desired type is provided at the bottom of each chute, which is shown herein as a series of bars 3, preferably triangular in shape. These bars may be rotated in unison by a chain 5 driven from any desired source of power and engaging sprocket wheels 4 on the bars. These bars 3 are so designed that any predetermined distance may be maintained between them at all times during rotation, and in practice the design is such that very little, if any, of the nitrocellulose falls between the bars. It will be noted that the feeding device is adapted to move forward only a comparatively small amount of nitrocellulose even though the entire chute be filled with nitrocellulose, the feeding device moving the nitrocellulose at the bottom of the mass adjacent the device, the mass gradually settling until it all has been fed. The speed of operation of the feeding device is adjusted to feed just the proper amount to be handled effectively by the mixing device.

Adjacent the end of each feeding device is a lump-breaking device of any desired type, which, in the present embodiment, takes the form of a toothed wheel 6 adapted to take the nitrocellulose from the feeding device and force it through a vertical rake 7, thereby breaking any lumps in the nitrocellulose. To avoid breakage, the rake 7 is hung loosely, its weight affording sufficient resistance to break any lumps which ordinarily occur.

From both lump-breaking devices, the nitrocellulose drops through a passage 8 to the mixing device, where the nitrocellulose is mixed thoroughly with water, drowned, and impelled or forced through a pipe 11 to washing machine W. This thorough mixing together of the water and nitrocellulose (which is heavier than water) suspends the fibers of the nitrocellulose in the water so that the mixture flows freely through the conveying pipe or pipes without clogging.

This also effectually drowns the nitrocellulose so that there is no danger of its decomposing. The water preferably reaches the bladed screw 9 of the mixing device from a passage 13 beneath the conveyer, and is supplied by a pipe 12 (which may be perforated if desired) at the upper end of the passage, so that any particles of nitrocellulose which might fall through the bars are washed to the mixing device. 75

The mixing device in the present embodiment takes the form of a screw 9, the blades of which are pitched at such an angle as to force the nitrocellulose down against the sides of the bowl 10 in which it is mounted, 80 which action churns the nitrocellulose and water together so that a perfect mixture is obtained characterized by the suspension of the individual fibers in the water. The mixture is discharged through a pipe 11 preferably 85 leading from near the bottom of the bowl 10 which pipe also preferably is placed tangentially to said screw 9. When the pipe is located near the bottom of the bowl it preferably is provided with a trap outside the 90 bowl as shown in Fig. 1, so that the fluid level within the bowl is maintained at desired height and the corrosive, acid fumes prevented from escaping into the pipe and subsequent apparatus. It is obvious that the 95 mixing and propelling may be performed by separate devices of similar or of different types, such, for example, as two separate screws or paddles or by a jet or jets of liquid or gas properly placed and arranged. 100

The entire apparatus is inclosed in a casting which prevents the escape of acid fumes except through a flue 14 adapted for that purpose.

Although I have illustrated my invention 105 by one embodiment thereof, it is not to be limited to such embodiment, which is chosen only for purposes of illustration, my invention consisting of an apparatus for conveying nitrocellulose from a fluid-extracting 110 apparatus to a washing machine without danger of the nitrocellulose decomposing or likelihood of the conveying pipes clogging, the nitrocellulose being fed to the mixing device in required quantities and condition, 115 drowned and suspended in water, and forced or impelled through a pipe.

Having described one embodiment of my invention, what I claim and desire to secure by Letters Patent is:

1. In an apparatus for treating nitrocellulose, the combination of means for so mixing said material and water as to suspend the material therein and impart to the said mixture velocity, and a conduit arranged 120 tangentially to said means for conveying away said mixture.

2. The combination of a fluid-extracting apparatus, a washing apparatus, and means to convey nitrocellulose from said fluid-ex- 130

- tracting apparatus to said washing apparatus without permitting said nitrocellulose to decompose, and to confine the fumes from said nitrocellulose comprising a mechanical feeding device.
3. The combination of a fluid-extracting apparatus, a washing apparatus, mechanical means to drown and convey material from said fluid-extracting apparatus to said washing apparatus, and means to inclose said first-named means to confine and carry away the fumes therefrom.
4. The combination of a fluid-extracting apparatus, a washing apparatus, and means to drown and convey material from said fluid-extracting apparatus to said washing apparatus comprising a clam shell adapted to form when closed a chute closed at the top.
5. The combination of a fluid-extracting apparatus, a washing apparatus, and means to drown and convey material from said fluid-extracting apparatus to said washing apparatus comprising a chute increasing in cross-section from top to bottom.
6. The combination of a fluid-extracting apparatus, a washing apparatus, and means to drown and convey material from said fluid-extracting apparatus to said washing apparatus comprising a chute and a feeding device at the bottom of said chute.
7. The combination of a fluid-extracting apparatus, a washing apparatus, and means to drown and convey material from said fluid-extracting apparatus to said washing apparatus comprising a device for breaking the lumps in said material.
8. The combination of a fluid-extracting apparatus, a washing apparatus, and means to drown and convey material from said fluid-extracting apparatus to said washing apparatus comprising a device for mixing said material with water and forcefully impelling said mixture, and a conduit tangential to said device through which said mixture is forced.
9. The combination of a fluid-extracting apparatus, a washing apparatus, and means to drown and convey material from said fluid-extracting apparatus to said washing apparatus comprising a device for suspending said material in water and forcefully impelling said material.
10. The combination of a fluid-extracting apparatus, a washing apparatus, and means to drown and convey material from said fluid-extracting apparatus to said washing apparatus comprising a device for suspending said material in water and forcefully impelling said mixture, and a conduit leading from near the bottom of said device provided with a trap to maintain the desired level in said device.
11. The combination of a fluid-extracting apparatus, a washing apparatus, and means to drown and convey material from said fluid-extracting apparatus to said washing apparatus comprising a device for suspending said material in water and forcefully impelling said mixture, and a conduit leading from near the bottom of said device provided with a trap to maintain the desired level in said device.
12. The combination of a fluid-extracting apparatus, a washing apparatus, and means to drown and convey material from said fluid-extracting apparatus to said washing apparatus comprising a clam shell adapted to form when closed a chute closed at the top, a chute beneath the clam shell, and a feeding device at the bottom of said chute.
13. The combination of a fluid-extracting apparatus, a washing apparatus, and means to drown and convey material from said fluid-extracting apparatus to said washing apparatus comprising a clam shell adapted to form when closed a chute closed at the top, a chute beneath the clam shell, a feeding device at the bottom of said chute, and a device for breaking lumps in said material.
14. The combination of a fluid-extracting apparatus, a washing apparatus, and means to drown and convey material from said fluid-extracting apparatus to said washing apparatus comprising a clam shell adapted to form when closed a chute closed at the top, a chute beneath the clam shell, a feeding device at the bottom of said chute, a device for breaking lumps in said material, and a device for mixing said material with water.
15. The combination of a fluid-extracting apparatus, a washing apparatus, and means to drown and convey material from said fluid-extracting apparatus to said washing apparatus comprising a clam shell adapted to form when closed a chute closed at the top, a chute beneath the clam shell, a feeding device at the bottom of said chute, a device for breaking lumps in said material, and a device for suspending said material in water.
16. The combination of a fluid-extracting apparatus, a washing apparatus, and means to drown and convey material from said fluid-extracting apparatus to said washing apparatus comprising a clam shell adapted to form when closed a chute closed at the top, a chute beneath the clam shell, a feeding device at the bottom of said chute, a device for breaking lumps in said material, and a device for mixing said material with water and forcefully impelling said mixture.
17. The combination of a fluid-extracting apparatus, a washing apparatus, and means to drown and convey material from said fluid-extracting apparatus to said washing apparatus comprising a clam shell adapted to form when closed a chute closed at the top, a chute beneath the clam shell, a feeding device at the bottom of said chute, a device for breaking lumps in said material, and a device for suspending said material in water.

- to form when closed a chute closed at the top, a chute beneath the clam shell, a feeding device at the bottom of said chute, a device for breaking lumps in said material, and a device for suspending said material in water and forcefully impelling said mixture. 5 for mixing said material with water and 65 forcefully impelling said mixture, and a pipe tangential to said last-named device to convey away said mixture.
18. The combination of a fluid-extracting apparatus, a washing apparatus, and means to drown and convey material from 10 said fluid-extracting apparatus to said washing apparatus comprising a clam shell adapted to form when closed a chute closed at the top, a chute beneath the clam shell, a feeding device at the bottom of said chute, 15 a device for breaking lumps in said material, a device for mixing said material with water and forcefully impelling said mixture, and a pipe tangential to said last-named device to convey away said mixture.
19. The combination of a fluid-extracting apparatus, a washing apparatus, and means to drown and convey material from 20 said fluid-extracting apparatus to said washing apparatus comprising a clam shell adapted to form when closed a chute closed at the top, a chute beneath the clam shell, a feeding device at the bottom of said chute, a device for breaking lumps in said material, a 25 device for suspending said material in water and forcefully impelling said mixture, and a pipe tangential to said last-named device to convey away said mixture.
20. The combination of a fluid-extracting apparatus, a washing apparatus, and means 30 to drown and convey material from said fluid-extracting apparatus to said washing apparatus comprising a clam shell adapted to form when closed a chute closed at the top, a chute beneath the clam shell, a feeding device at the bottom of said chute, a device for breaking lumps in said material, a 35 device for suspending said material in water and forcefully impelling said mixture, and a pipe tangential to said last-named device to convey away said mixture.
21. The combination of a fluid-extracting apparatus, a washing apparatus, and means 40 to drown and convey material from said fluid-extracting apparatus to said washing apparatus comprising a chute, a feeding device at the bottom of said chute, a device for breaking lumps in said material, and a 45 device for mixing said material with water.
22. The combination of a fluid-extracting apparatus, a washing apparatus, and means 50 to drown and convey material from said fluid-extracting apparatus to said washing apparatus comprising a chute, a feeding device at the bottom of said chute, a device 55 for breaking lumps in said material, and a device for mixing said material with water and forcefully impelling said mixture.
23. The combination of a fluid-extracting apparatus, a washing apparatus, and means 60 to drown and convey material from said fluid-extracting apparatus to said washing apparatus comprising a chute, a feeding device at the bottom of said chute, a device 65 for breaking lumps in said material, and a device for mixing said material with water and forcefully impelling said mixture.
24. The combination of a fluid-extracting apparatus, a washing apparatus, and means 70 to drown and convey material from said fluid-extracting apparatus to said washing apparatus comprising a feeding device, and a device for breaking lumps in said material.
25. The combination of a fluid-extracting 75 apparatus, a washing apparatus, and means to drown and convey material from said fluid-extracting apparatus to said washing apparatus comprising a feeding device, a device for breaking lumps in said material, 80 and a device for mixing said material with water.
26. The combination of a fluid-extracting apparatus, a washing apparatus, and means to drown and convey material from said 85 fluid-extracting apparatus to said washing apparatus comprising a feeding device, a device for breaking lumps in said material, and a device for mixing said material with water and forcefully impelling said mixture. 90
27. The combination of a fluid-extracting apparatus, a washing apparatus, and means to drown and convey material from said 95 fluid-extracting apparatus to said washing apparatus comprising a feeding device, a device for breaking lumps in said material, a device for mixing said material with water and forcefully impelling said mixture, and a pipe tangential to said last-named device to convey away said mixture. 100
28. The combination of a fluid-extracting apparatus, a washing apparatus, and means to drown and convey material from said fluid-extracting apparatus to said washing apparatus comprising a device for breaking lumps in said material, and a device for 105 mixing said material with water.
29. The combination of a fluid-extracting apparatus, a washing apparatus, and means to drown and convey material from said fluid-extracting apparatus to said washing apparatus comprising a device for breaking lumps in said material, and a device for 110 mixing said material with water and forcefully impelling said mixture. 115
30. The combination of a fluid-extracting apparatus, a washing apparatus, and means to drown and convey material from said fluid-extracting apparatus to said washing apparatus comprising a feeding device, a 120 device for breaking lumps in said material, a device for mixing said material with water and forcefully impelling said mixture, and a pipe tangential to said last-named device to convey away said mixture. 125
31. The combination of a fluid-extracting apparatus, a washing apparatus, and means to drown and convey material from said

- fluid-extracting apparatus to said washing apparatus comprising a device for breaking lumps in said material and a device for mixing said material with water.
- 5 32. The combination of a fluid-extracting apparatus, a washing apparatus, and means to drown and convey material from said fluid-extracting apparatus to said washing apparatus comprising a device for breaking 10 lumps in said material, and a device for mixing said material with water and forcefully impelling said mixture.
33. The combination of a fluid-extracting apparatus, a washing apparatus, and means 15 to drown and convey material from said fluid-extracting apparatus to said washing apparatus comprising a device for breaking lumps in said material, a device for mixing said material with water and forcefully impelling said mixture, and a pipe tangential 20 to said last-named device to convey away said mixture.
34. The combination of a fluid-extracting apparatus, a washing apparatus, and means 25 to drown and convey material from said fluid-extracting apparatus to said washing apparatus comprising a feeding device and a device for mixing said material with water and forcefully impelling said mixture.
- 30 35. The combination of a fluid-extracting apparatus, a washing apparatus, and means to drown and convey material from said fluid-extracting apparatus to said washing apparatus comprising a feeding device, a 35 device for mixing said material with water and forcefully impelling said mixture, and a pipe tangential to said last-named device to convey away said mixture.
36. In an apparatus for mixing materials 40 with fluid, means to drown and convey material comprising a series of substantially triangular-shaped bars and means to rotate said bars.
37. In an apparatus for mixing materials with fluid, means to drown and convey material comprising a feeding device and means to convey water beneath said device. 45
38. In an apparatus for mixing materials with fluid, means to drown and convey material comprising a series of loosely hung 50 spaced fingers and means to force material against said fingers.
39. In an apparatus for mixing materials with fluid, means to drown and convey material comprising a mixing device, means to 55 convey water to said device, means to convey material to said device, and a tangential pipe adjacent said device to convey away the resulting mixture.
40. In an apparatus for mixing materials 60 with fluid, means to drown and convey material comprising an impelling device comprising a device to suspend material in water and to impel the mixture through a tangential pipe. 65
41. In an apparatus for mixing materials with fluid, means to drown and convey material comprising a mixing device, and a feeding device adapted to convey predetermined amounts of material from the bottom 70 of a mass of material to said mixing device.
42. In an apparatus for mixing materials with fluid of the character described, means to drown and convey material comprising an impelling device, and a feeding device adapted to convey predetermined amounts 75 of material from the bottom of a mass of material to said impelling device.
- In testimony that I claim the foregoing I have hereunto set my hand.

EVARTS G. LOOMIS.
